UNITED STATES PATENT OFFICE.

IVERSON G. TEDDER, OF HOLLAND, TEXAS.

DRAFT-EQUALIZER.

1,003,160.

Specification of Letters Patent.

Patented Sept. 12, 1911.

Application filed June 17, 1911. Serial No. 633,664.

To all whom it may concern:

Be it known that I, IVERSON G. TEDDER, a citizen of the United States, residing at Holland, in the county of Bell and State 5 of Texas, have invented certain new and useful Improvements in Draft-Equalizers, of which the following is a specification.

The draft device which is the subject of the present invention is designed for working 10 three horses abreast so that each horse can walk between the rows when plowing or planting, and to this end it consists in a novel construction and arrangement of parts to be hereinafter described and claimed, and 15 illustrated in the accompanying drawing forming a part of this specification.

The invention also has for its object to provide a pivoted draft tongue and improved means for operating the same.

20 In the drawing, Figure 1 is a plan view of the invention, partly broken away. Fig. 2 is a section on the line 2—2 of Fig. 1.

Referring specifically to the drawing, 5 denotes the wheels of a planter, plow, or 25 other agricultural implement to which the invention is applied, and 6 denotes the axle of said wheels. Rigidly secured to the axle 6, midway between the ends thereof, is a stub tongue 7 extending forwardly from the 30 axle, and carrying the main tongue 8.

The following connection is provided between the tongues 7 and 8: To one side of the tongue 7 is bolted or otherwise rigidly fastened a brace 9 having a lateral extension 10 terminating in forwardly and rearwardly 35 extending branches 11 and 12, respectively. To the branch 11 is bolted or otherwise rigidly secured a short supporting beam or block 13 on top of which the tongue 8 is 40 pivoted as indicated at 14, the pivot being arranged to permit the tongue to swing sidewise. The branch 12 is fastened to the axle 6 by a clip 15. A brace 16 is also secured to the forward end of the tongue 7, and extends 45 sidewise across the butt end of the tongue 8 behind the pivot 14, and thence extends downwardly to one side of the tongue and the supporting beam, it being made fast by a bolt or other suitable fastening 17 passing through the branch 11 and the supporting beam. A spacing block 18 is interposed between the brace and the branch. This block spaces the downturned portion of the brace from the butt end of the 55 tongue 8 and permits its sidewise swing.

A toggle connection is provided between

the tongue 7 and the butt end of the tongue 8, said connection comprising pivotally connected links 19, one of said links being connected to the tongue 7 and the other link to the tongue 8. To the branch 12 is pivoted a hand lever 20 which is connected by a link 21 to the toggle links at the pivotal connection therebetween. Suitable means 22 are provided for locking the hand lever in adjusted position. The herein described toggle connection swings the tongue 8 sidewise upon operating the hand lever, and the tongue is locked in adjusted position upon locking the hand lever.

The forward end of the tongue 7 carries a draft tree 23 to the ends of which are connected evener bars 24 which latter carry swingle-trees 25 at their outer ends. Between the swingle-trees 25 is located a 75 swingle-tree 26 which is connected by links 27 to the inner ends of the evener bars. The swingle-tree 26 and one of the swingle-trees 25 are located on one side of the tongue 8, and the other swingle-tree 25 is located on 80 the other side of the tongue.

At the forward end of the tongue 8 is a lever 28 which is pivoted midway between its ends to the outer end of the bracket 29 secured to the tongue 8 and extending from 85 that side thereof on which the swingle-tree 26 and its companion swingle-tree 25 are located. This lever carries neck yokes 30 at its ends. The adjacent ends of the neck yokes carry rings 31 for attachment of the 90 breast straps of one of the draft animals, and the other ends of the neck yokes carry rings 32 for attachment of the breast straps of the other two draft animals. It will be noted that the rings 31 and one of the rings 32 are located on the same side of the tongue 8 as the swingle-tree 26 and its companion swingle-tree 25, and that the other ring 32 is located on the other side of the tongue. This arrangement enables one of 95 the animals to be hitched on one side of the tongue and the other two animals on the other side, and it is therefore possible to work three horses abreast so that each horse can walk between the rows when plowing or planting, and the draft is evenly distributed.

The invention is without complicated parts, and can be readily applied to any 110 implement having a draft tongue, it being necessary only to cut off a portion of said tongue, the cut off portion being then con-

nected to the remaining stub tongue by the braces herein described.

I claim:

1. The combination with a vehicle, of a stub tongue, a brace secured to the stub tongue and extending laterally therefrom, the outer end of the brace having a rearwardly extending branch, a supporting beam carried by the outer end of the brace, a draft tongue pivoted to the beam, a toggle connection between the butt end of the pivoted tongue and the stub tongue, and a hand lever carried by the aforesaid rearwardly extending bracket and operatively connected to the toggle.
2. The combination with a vehicle, of a stub tongue, a brace fastened to the stub tongue and having a lateral extension terminating in forwardly and rearwardly ex-

tending branches, the latter being fastened to the axle of the vehicle, a supporting block carried by the forwardly extending branch, a draft tongue pivoted to the supporting block, a brace secured to the stub tongue and extending sidewise across the butt end of the draft tongue, and fastened to the supporting block, said last mentioned brace being spaced from the draft tongue, draft devices being carried by the draft tongue, and means for swinging said tongue on its pivot.

In testimony whereof I affix my signature in presence of two witnesses.

IVERSON G. TEDDER.
